UNITED STATES PATENT OFFICE.

HENRY BADDELEY COOPER, OF COLUMBUS, OHIO.

HOSE-SUPPORTER.

No. 813,621.

Specification of Letters Patent.

Patented Feb. 27, 1906.

Application filed November 18, 1904. Serial No. 233,278.

To all whom it may concern:

Be it known that I, HENRY BADDELEY COOPER, a citizen of the United States, residing at Columbus, Ohio, have invented certain new and useful Improvements in Hose-Supporters, of which the following is a specification.

My invention relates to improvements in hose-supporters; and the object of the invention is to provide a simple and convenient form of support which will yield or accommodate itself to every movement of the body and which will relieve the stockings of the heavy strain arising from the motion of the body, as in walking or stooping.

The invention is illustrated in the accompanying drawings, in which—

Figure 1 is a front view. Figs. 2, 3, and 4 are detail views. Fig. 5 is a view of a modification in which the belt is not used. Fig. 6 is a detail view of the belt shown in Fig. 1.

According to my said invention I provide a front portion or supporting member 5, of cloth.

The devices for supporting the stocking or hose are connected to this front portion 5, and these I will now proceed to describe in detail. A short tape 6 is secured to the central part of the lower edge of the portion 5, this tape preferably being in the form of a loop. In this tape is held a metallic loop 7, through which freely passes the central portion of a flexible member—such, for instance, as a tape 8, the ends 8^a of which are secured to the lower corners of the portion 5. The depending portions 8^b of this member 8 between the central and side fastenings are each engaged by or passed through a metallic loop 9, and each of these loops also supports an elastic tape 10. To the lower end of each elastic tape is secured a pair of tapes 11, having connecting-clips 12 at their lower ends for connecting to the opposite sides of the stocking.

I prefer to make each elastic tape 10 double for its whole length and pass the two ends through between the three bars 13^a, 12^b, and 13^c of a holding device, such as the buckle 13^b, to the central bar of which the tapes 11 are connected. The upper bar of each clip is 50 preferably provided with teeth, so that after the elastic tapes have been drawn through to secure the proper adjustment they will be firmly held.

In order to cover the metallic loops 7 and 9 and provide an ornamental connection, the said loops are inclosed by box-like inclosing

members 14, as shown more in detail in Figs. 2, 3, and 4. These inclosing members or devices each consist of a single piece of sheet metal bent to provide slightly-flaring sides 60 14^a. One side of the metallic loops 7 or 9 is placed in the bend and held therein by clamping the metal tightly around it, and the sides are slotted parallel and in proximity to the said bar of the loop to permit the passage of 65 the tape. The other bar of the loop will thus be concealed between the side walls of the inclosing member, and the elastic tape extends down through the open mouth. I prefer to close in the ends of members 14 by forming 70 integral extensions, which are bent to form the closed ends 14^b. This front portion 5 may be secured in any suitable manner, as by safety-pins or any other form of detachable connection, directly to the front of a corset, 75 as shown in Fig. 5; but I find it desirable to use it in connection with a belt of improved form, as will now be described.

To the upper corners of the portion 5 are secured looped tapes 16, which are passed 80 through metallic loops or clips 17. Through these loops 17 are passed the looped ends of side tapes 18, which are made adjustable by the slides 19. This adjustment is rendered possible by securing each slide 19 to one end 85 of the corresponding tape and having said slide movable on the intermediate portion of the tape, but held normally against movement by frictional engagement therewith. By this arrangement the side tapes or parts 90 of the belt may be readily adjusted to fit any-sized person, and it is not necessary for a merchant to carry on hand a stock of different sizes or for a customer to ask for any particular size.

The side tapes connect at the rear with a back portion 20, of cloth or other suitable material, and I prefer to make the connection in the shape of a ball-and-socket fastener 21, which forms a readily-detachable and yet secure connection.

To the front and back portions of the belt I secure clips for holding a napkin. Each of these preferably consists of a rectangular frame 22, large enough to permit of the end of 105 a napkin being inserted therethrough, after which it will be held by a sliding cross-bar 23. Each of these frames is connected to a tab 24, of suitable material, which is connected to the front or back portion by a detachable 110 connection, such as a ball-and-socket fastener 25.

Having thus described my invention, what I claim is—

1. In combination, a belt comprising front and back portions, metallic loops connected to the upper corners of one of said portions, side tapes threaded through said loops with means for adjusting them and having their opposite ends detachably connected to the other of said portions, a double-looped flexible member depending from the front portion, and a hose-supporting member depending from each loop and having a sliding connection therewith, substantially as described.
2. In combination, a front portion, metallic loops connected to the upper corners thereof, side tapes threaded through said loops with means for adjusting them, detachable connecting means between the other ends of said tapes, a double-looped flexible member depending from the front portion, a metallic loop carried by each loop of said double-looped member, an elastic member threaded through each of said metallic loops and having depending coextensive portions or ends, and a clip carrying hose-engaging devices adjustably connected to both said coextensive portions, substantially as described.
3. In combination, a belt comprising front and back portions, metallic loops connected to the upper corners of one of said portions, side tapes threaded through said loops with means for adjusting them and having their opposite ends detachably connected to the other of said portions, a double-looped member depending from the front portion, a me-

tallic loop carried by each loop of said double-looped member, an elastic member threaded through each of said metallic loops, and having depending coextensive portions or ends, and a holding means carrying hose-supporting members adjustably connected to both said coextensive portions or ends, substantially as described.

4. In a hose-supporter having two looped members slidably connected together, means for effecting such sliding connection comprising a metallic loop, around the lower bar of which one of such members passes, a sheet-metal casing extending to one side from said metal loop and having closed-in sides and a mouth opening away from said metal loop, said other looped member extending through said mouth and being slidably held within the casing and inclosed on all sides thereby, substantially as described.

5. In a hose-supporter having two looped flexible members slidably connected together, means for effecting such sliding connection comprising a metallic loop and a sheet-metal casing clamped around one bar of said loop and inclosing the other bar, and having parallel slots in its sides through which one of said members passes, substantially as described.

In testimony whereof I affix my signature in presence of two witnesses.

HENRY BADDELEY COOPER.
